UNITED STATES PATENT OFFICE.

EDWARD HINDLEY, SAMUEL WALKER, AND MARSHALL ROSE, OF STOCKPORT, ENGLAND.

APPARATUS FOR DYEING, &c.

SPECIFICATION forming part of Letters Patent No. 706,657, dated August 12, 1902.

Application filed October 28, 1901. Serial No. 80,278. (No model.)

To all whom it may concern:

Be it known that we, EDWARD HINDLEY, SAMUEL WALKER, and MARSHALL ROSE, subjects of the King of Great Britain, and residents of Stockport, in the county of Chester, England, (whose post-office address is Howard street, Stockport, aforesaid,) have invented new and useful Improvements in Apparatus for Dyeing, Scouring, Bleaching, and otherwise Treating Yarn in Cop or other Similar Compact Form, (for which we have made application for patent in Great Britain, No. 6,666, dated March 30, 1901,) of which the following is a specification.

15 Our invention relates to that class of apparatus for dyeing, scouring, bleaching, and otherwise treating yarn in cop or other similar compact form in which it is placed on hollow perforated tubes or skewers, by means of 20 which latter and the assistance of suitable pump or pumps the yarn is impregnated with dye or other suitable liquor by drawing or forcing it through and ultimately extracting the superfluous liquor from the same; and 25 the objects of our improvements are to provide means whereby the liquor can be alternately drawn and forced through the cops in a vertical position by one pump without reversing the same and at any temperature of 30 the liquor without a lid or cover on the vessel in which the cops are treated, thus insuring safety from accidents and providing a cheap, handy, and effective apparatus. We attain these objects by the mechanism illustrated in the accompanying drawings, in 35 which—

Figure 1 is a side view, partly in section; Fig. 2, a plan of our improved apparatus complete, and Fig. 3 a side view of the portable 40 chambers or cop-carriers removed therefrom.

Similar letters refer to similar parts throughout the several views.

In carrying out our invention and referring to the figures generally we employ in an open 45 vessel *a* a suitable number of oblong or square portable chambers *b*—say two—in the top of which are a number of holes in which are placed the tubes or skewers *c*, which hold the cops vertically in position during the process 50 of dyeing or bleaching, and which chambers

thus form the cop-carriers. The top of each of the said chambers is furnished with two pillars *t*, adapted to receive a plate *d*, which serves to hold the spindle or skewers *c* in position on the said chambers when forcing the liquor through the cops. The said plates are secured to the said pillars by means of the handle-shaped nuts *e*, which also facilitate the lifting of the said chambers in and out of the said vessel. The bottom of the said vessel and that of each of the said chambers are formed with the male and female tube connections *f* and *g*, respectively, the former receiving the latter, so as to permit of readily placing the said chamber into the said vessel and removing it therefrom and of drawing or forcing the liquor through the said chambers. To the said male connections is secured a pipe *h*, communicating with the suction and by a branch pipe *i* with the delivery of a suitable pump *k*. Between the said branch pipe and the suction of the said pump a three-way tap *l* is employed and another, *m*, between the branch pipe *i* and the delivery of the said pump. The side of the vessel *a* is connected by the pipe *n* with the tap *m* and the said pipe by a branch pipe *o* with the tap *l*, while the bottom of the vessel is furnished with a steam-inlet *p* and liquor-draw-off cock *q*. The said pump and vessel are preferably secured to a common base-plate *u*.

The apparatus described operates as follows: When it is desired to draw the liquor through the cops, the three-way taps *l* and *m* are so set (see respective handles *r* and *s*, drawn in full lines) that the liquor passes through the pipe *h*, tap *l*, into the pump *k*, and by the latter is forced through tap *m* and pipe *n* back into the vessel *a*. (See arrows in full lines.) When it is desired to force the liquor through the cops, the three-way taps *l* and *m* are so set (see respective handles *r* and *s*, shown in dotted lines) that the liquor is drawn from the vessel *a* through pipe *n*, branch pipe *o*, tap *l*, pump *k*, tap *m*, branch pipe *i*, and pipe *h* into the said chambers *b*. (See arrows in dotted lines.)

What we claim as our invention, and desire to secure by Letters Patent, is—
In apparatus for dyeing, scouring, bleach-

ing and otherwise treating yarn in cop or other similar compact form, a liquor vessel having at the bottom and the side liquor connections, a pump having at the suction and 5 delivery respectively a three-way tap, a pipe between the former tap and the said bottom connections having a branch leading to the said tap at the delivery end and a pipe between the latter tap and the said side connection having a branch leading to the said tap at the suction end of the said pump, all com-

bined substantially as and for the purpose set forth.

In witness whereof we have hereunto set our hands in presence of two witnesses.

EDWARD HINDLEY.
SAMUEL WALKER.
MARSHALL ROSE.
